WORK-HOLDING DEVICE

Harry D. Manning, Kalamazoo, Mich.

Application March 8, 1943, Serial No. 478,466

3 Claims. (Cl. 144—305)

This invention relates to clamps and clamping devices and particularly to the type thereof providing means effecting quick manipulation combined with positive action.

The principal object of this invention is to provide a clamp of the type mentioned which may be moved into and out of clamping position in a minimum time and with minimum effort.

A major object of this invention is to provide a clamp of the type described in which the clamping members when in engaging position are positively engaged with no opportunity for slipping.

A further object of this invention is to provide a clamp of the type described which is sturdy and strong and is free of complex and/or delicate parts.

A further object of this invention is to provide a clamp of the type described whose parts are relatively simple in shape and can be rapidly fabricated by the use of ordinary machine tools.

A further object of this invention is to provide a clamp of the type described which can be manufactured rapidly and cheaply yet be sturdy, strong, rapid in use, and positive.

All of these desirable ends I have secured by the clamp described hereinafter and illustrated by the accompanying drawing.

Referring now to the drawing:

Figure 1 shows a side view of the portion of an ordinary C-clamp upon which the adjustable holding means is mounted.

Figure 2 shows a view partially in section taken at line II—II of Figure 1.

Figure 3 is a partial section taken on line III—III of Figure 2, and in an enlarged scale.

Figure 4 is a plan view of one of the internal members.

Figure 5 is a plan view of another of the internal members.

Figure 6 is a partial section taken at line VI—VI of Figure 3.

The use of C-clamps being very old, there has long been a desire and need for a satisfactory means for making them quick and easy to operate without sacrificing positiveness in holding. The conventional screw type is slow but has hitherto been unexcelled in its positive holding. The presently known quick-acting types are legion in number but are either prohibitively expensive to manufacture, impractical to operate, or are insufficiently reliable in holding to be trustworthy. Many types have been suggested and many types are now in use, but none to my knowledge adequately meet the above requirements.

The hereinafter disclosed invention does meet

these requirements and is therefore considered both new and useful. Its principle is illustrated by assuming application to a C-clamp, but it can readily be applied to any other device, such as a vise, wherein adjustable holding means are desired. Such applications are within the scope of this disclosure and the hereinafter appended claims, excepting only as such claims may be otherwise expressly limited.

In Figure 1 the C portion of the clamp is indicated at 1 and it has an enlarged portion at 1—a for the reception of the movable clamping rod or shank 3. This shank is manipulated by handle 16, which is of any conventional kind and affixed in any conventional manner; the work engaging end, or foot, 17 may be of any conventional type to bear in the usual manner against a suitable conventional gripping surface at the other extremity of the C. Since the general construction of a C-clamp is well known, no further reference need be made to it. My invention concerns the means for accommodating the shank 3 within portion 1—a of the C, moving it into gripping position, tightening it therein, loosening it again, and removing it from gripping position, and hence only the parts of the clamp related to such functions need be, and will be, detailed.

Enlarged portion 1—a has an opening therethrough of size suitable to accommodate sleeve 2. Said opening is threaded internally and sleeve 2 is threaded externally at 2—a for mutual interaction so that rotation of sleeve 2 will move it upwardly or downwardly (as same is illustrated in Figure 1) according to the direction of rotation.

Shank 3 is square in cross-section but regularly spaced portions 10 are machined to become circular in cross-section, as best shown by the sectioned portion of Figure 2. In this manner a series of teeth 11 are formed on what then becomes a round shank, but a section through any of the teeth is square. It will be noted that the teeth are oppositely placed and do not advance in the manner of a screw thread; they are formed by a simple and direct machining operation which promotes inexpensive construction.

Returning now to the construction of sleeve 2, with particular reference to Figure 3, it will be seen that an internal axial opening extends throughout its length. One or more channels 18 are placed, as by broaching, along the interior of said opening, for a purpose to appear hereinafter, and are conveniently made to extend the full length of the sleeve 2. The interior diameter of sleeve 2 is uniform throughout its length.

Within sleeve 2 are located a series of ring-like

members, or plates, 7 and 8. These are placed alternately within said sleeve with their lugs 9 in channels 18 holding them from turning with respect to sleeve 2; the number of such plates will depend upon the strength desired to be available to the clamp. As the desired strength is increased, the number of necessary plates will increase and will in turn require a corresponding increase in the length of sleeve 2. A sleeve or collet 25 may fill the remaining space within sleeve 2, excepting only the ends, which are occupied by rings 4 and 4a threadedly secured in place and holding all of the foregoing within said sleeve. Rings 4 and 4a have interior diameters less than the external diameter of collet 25 and plates 7 and 8 but great enough to permit shank 3 to rotate freely therewith.

Plates 7 and 8 each have a central opening and these plates differ from each other only in the shape of their respective central openings. The openings 6 in plates 8 are square and of size slightly greater than the size of shank 3, so that shank 3, when turned into register therewith, may pass freely therethrough but will fit closely therewith (Figure 2). With a shank of $\frac{1}{2}$ inch square measurement, opening 6 may be made approximately $\frac{17}{32}$ inch square.

Plates 7 are provided with central opening 5 of the generally wide cross-shape shown in Figure 4. Portions 22 of said opening are arcs centered in the axis of shank 3 when same is in position within said plates as shown in Figure 6. The radius of said arcs is sufficient to permit teeth 11 to clear these portions of plates 7 as shown in Figure 6. Arcs 22 terminate at inwardly extending surfaces 23 and 23a which meet to define extending portions 24. Surfaces 23 and 23a may be of any shape effective to intercept teeth 11 of shank 3 and limit rotation thereof in either direction to the arcuate distance between said surfaces 23 and 23a. Conveniently, and as shown, surfaces 23 and 23a may be shaped to lie flat against the respectively contacting surfaces of teeth 11 when shank 3 has by rotation in either direction reached the limit defined by said surfaces 23 and 23a. One of these positions is illustrated in Figure 6.

In assembling the sleeve unit with ring 4a and collet 25 in place, plates 7 and 8 in the desired number are slipped into said sleeve from end 4 with their lugs 9 lying in channels 18, and the sleeve is filled slightly more than to the inner surface of ring 4. Ring 4 is then threaded into place and tightened down onto plates 7 and 8 to hold them firmly against collet 25. Said rings 4 and 4a may be manipulated in any convenient manner, as by providing openings therein to receive a small spanner wrench. Whenever desirable, it is obviously easy to remove retaining rings 4 or 4a and all of the parts contained between them for replacement or cleaning.

Since lugs 9 appear on both series of plates, the proper positioning of the two series with respect to each other is easy and positive. When so installed, the respective openings will lie with respect to each other as shown in Figure 6, wherein the solid lines represent the section indicated and the dotted lines superimposed thereon represent the outline of the central opening of plates 8.

Although normally plates 7 and 8 will be of thickness equal to each other and to the thickness of teeth and spaces 11 and 10, it is obviously possible to secure easier punching by making each of either plates 7 or 8, or both, of thinner

material and piling the units to secure the arrangement shown. For example, plates 7 and 8 may be made of material $\frac{1}{3}$ of the thickness of teeth or spaces 10, in which case three plates of shape 7 will be used, then three plates of shape 8 will be used, then three plates of shape 7, and so on until the required number is obtained.

Collet 25 is a useful but not indispensable addition to the clamp. Externally it is round and of diameter to enter easily into the internal opening of sleeve 2. Internally said collet has a square opening fitting slidably but closely around the square section of shank 3 represented by teeth 11 (for example, $\frac{1}{64}$ inch clearance). A light spring 27 is fastened at one end in any convenient manner to collet 25, as by insertion of said one end at 20 into a small opening in the side of said collet 25; it is then wrapped several times around said collet to place it under tension and its other end inserted into an opening in ring 4a, as indicated at 21. In this way there is always a force urging rotation placed upon shank 3. It may, however, be omitted and the sleeve either shortened or entirely filled with plates 7 and 8.

The operation of this speed clamp is probably obvious from the description given thus far, but for the purpose of completeness it will be outlined.

The clamp is assembled with sleeve 2 holding ring 4, plates 7 and 8, collet 25, and ring 4a. Shank 3 extends through the openings within ring 4, plates 7 and 8, collet 25, and ring 4a, and the entire assembly is threadedly accommodated by the frame of clamp 1, or by the corresponding part of a vise or whatever other device is being used with this quick-acting mechanism. Shank 3 is rotated to bring the square outline of its teeth 11 into register with the corresponding outline of openings 6 in plates 8. It can then be manually, directly, and rapidly moved into such position that the clamp, or vise, lightly grips the object to be held by it. Shank 3 is then adjusted slightly if necessary to bring teeth 11 into register with plates 7 and rotated. If sleeve 25 is used its spring 27 will assist in this rotation of shank 3. By this rotation teeth 11 move clockwise as seen in Figure 6 toward the limits permitted by surfaces 23 of plates 7 and in so doing move out of register with the square openings of plates 8. Shank 3 thus can not move back away from the work, or otherwise move longitudinally with respect to sleeve 2. As shank 3 is further turned clockwise, as appearing in Figures 1 and 6, the teeth 11 will bear against adjacent surfaces 23 and urge plates 7 to move clockwise. This urging acts through lugs 9 of said rings 7 and causes sleeve 2 to turn clockwise by which it is advanced upward as same appears in Figure 1, thus to tighten shank 3 against the work being held. When it is desired to loosen the clamp, it is necessary only to turn shank 3 counter-clockwise to turn teeth 11 back into register with openings 6 in plates 8, whereupon the shank 3 may be instantly drawn backward as desired.

Particular attention is called to the fact that the above disclosed and described clamp, being rapid and positive in its operation, can be fabricated throughout by simple machining processes, such as lathe work, and by cold stamping. Its assembly is rapid and may be accurately effected by unskilled workmen. Hence, the cost of manufacture of this clamp

will be low, yet without sacrifice in speed of manipulation or positiveness of holding.

Obviously many variations within the scope of my invention will be at once evident to any skilled mechanic, or may be readily developed to meet a particular need, some of which have already been indicated:

Having thus fully disclosed and described my invention, I claim:

1. In a quick-acting clamp having a body part and work engaging means thereon, a threaded opening in said body part and an externally threaded sleeve accommodated therein; a series of contiguous plates of equal thickness within said sleeve perpendicular to the axis thereof, and a lug on each of said plates fitting into a channel in the interior of said sleeve and holding said plates against rotation with respect to said sleeve; means holding said group of plates against movement one way longitudinally of said sleeve and an externally threaded ring retained by internal threading within said sleeve holding said plates against movement the other way longitudinally of said sleeve; a square opening in alternate plates throughout the length of said group of plates and an opening in the remainder of said plates of the pattern of a wide cross having tapering limbs with arcuate ends; a square shank having cuts each of a width sufficient to accommodate one of the above-mentioned plates and spaced apart a distance equal to the thickness of the above-mentioned plates, said cuts defining a circular section providing oppositely spaced teeth on said shank which shank is located within said openings in said plates and extends axially through said sleeve; said openings in all of said plates being of size and alignment to provide a continuous channel of cross-sectional area sufficient to permit said shank in one rotative position to pass freely longitudinally therethrough and providing by the said cross-shaped openings in said second-named plates a series of recesses in the walls of said channels receiving the teeth of said shank in another rotative position thereof, and abutments within said recesses limiting rotative movement of said shank with respect to said sleeve; manipulative means on one end of said shank and work engaging means on the other end of said shank.

2. In a quick-acting, work-holding device having a body part including fixed work-engaging means; a threaded opening within said body part; an externally threaded sleeve accommodated within said opening; two groups of contacting plates of equal thickness within said sleeve perpendicular to the axis thereof, the individual plates of one group alternating with the individual plates of the other group; means holding said plates against rotation with respect to said sleeve; means holding said plates against movement longitudinally in either direction with respect to said sleeve; a central opening of one angular shape in each plate of one group of plates; a central opening of a larger and different angular shape in each plate of the second

group of plates; a shank member having a cross-section geometrically similar to, and slightly smaller than the first above-mentioned angular shape, and having also cuts, each cut defining a circular section of width sufficient to accommodate one of the above-mentioned plates and spaced apart a distance equal to the thickness of the above-mentioned plates, the portion of the shank between said cuts forming a series of 10 equally spaced and oppositely positioned teeth; said openings in all of said plates being of size and alignment providing a continuous channel of sufficient cross-sectional area to permit said shank in one rotative position to pass freely longitudinally therethrough and providing by the openings in the second named group of plates a series of recesses in the walls of said channel for the reception and engagement of the teeth of said shank in another rotative position thereof, and abutments within said recesses limiting rotation of said shank relative to said sleeve; manipulative means and work-engaging means operatively associated with said shank.

3. In a quick-acting, work-holding device having a body part and fixed work-engaging means thereon, a sleeve threadedly accommodated within a portion of said body part; a shank co-axial with, and partially rotatable, relative to said sleeve and having manipulative and work-engaging means operatively associated therewith; said shank having a series of oppositely positioned and equally spaced teeth each of a thickness equal to the spacing between the teeth, and means operative in one position for engaging said shank and said sleeve for unitary rotative movement and operative in another position for disengaging same; said last named means comprising: a group of plates within said sleeve held against both rotational and longitudinal movement with respect thereto; the thickness of each individual plate of the group being equal to the spacing between the teeth on said shank; an angular central opening in each alternate plate of the entire group, said opening being similar in cross-section to the shank and adapted to slidably but non-rotatably accommodate said shank, an angular central opening in each of the remaining alternately arranged plates of the entire group which openings are of shape different from the openings in said first-mentioned alternate plates, and which openings are defined by a plurality of arcs to rotatably accommodate said shank; shoulders between the contiguous arcs projecting into the opening and forming stops to arrest the rotation of said shank; said openings in all of said plates being of size and alignment to provide a continuous channel of sufficient cross-sectional area whereby said shank in one rotative position will pass freely axially therethrough, and by virtue of said openings and shoulders in the second named group of plates will in another rotative position of said shank cause said teeth to be engaged by said shoulders to lock said shank and sleeve for unitary rotative movement thereof.

HARRY D. MANNING.
